(57) **ABSTRACT**

A first substrate has recesses respectively provided at corner portions of a bottom surface. Outer electrodes each have an electrode body portion provided around an associated one of the recesses on the bottom surface. The electrode body portions each are made up of a plurality of laminated metal layers. A first metal layer located at an innermost side of the plurality of metal layers is formed on the bottom surface at a position spaced apart from a short-side ridge portion between the bottom surface and a side surface.

COIL COMPONENT

CROSS-REFERENCE TO RELATED APPLICATION

This application claims benefit of priority to Japanese Patent Application No. 2020-000973, filed Jan. 7, 2020, the entire contents of which is incorporated herein by reference.

BACKGROUND

Technical Field

The present disclosure relates to a coil component.

Background Art

Hitherto, electronic components are mounted on various electronic devices. For example, a laminated coil component is known as one of the electronic components, as described, for example, in International Publication No. 2013-031880). In the coil component of International Publication No. 2013-031880, outer electrodes are provided at four corners on the bottom surface of a substrate. Each of the outer electrodes is made up of a plurality of metal layers. Also, in the coil component of International Publication No. 2013-031880, ridge portions of the substrate and the like are chamfered by barrel polishing.

Incidentally, in the thus configured coil component, when chamfering is performed by barrel polishing or the like, surface layer parts of the outer electrodes in chamfering may be elongated on the bottom surface of the substrate. In this way, when there is an elongation in the outer electrodes, stress easily concentrates on that portion, so, when high temperature treatment is performed by means of mounting reflow or the like, a fracture of the substrate or cracks of the electrodes may occur. In this way, there remains room for improvement in terms of reliability.

SUMMARY

Accordingly, the present disclosure provides a coil component capable of contributing to improvement in reliability.

According to preferred embodiments of the present disclosure, a coil component includes a magnetic substrate having a rectangular bottom surface having a pair of long sides and a pair of short sides, a top surface located across from the bottom surface, and a pair of long-side side surfaces and a pair of short-side side surfaces each connecting the bottom surface and the top surface, a multilayer body having an electrically insulating layer formed on the top surface and a coil formed in the electrically insulating layer, and an outer electrode provided on the bottom surface. The magnetic substrate has a recess provided at a corner portion of the bottom surface. The outer electrode has an electrode body portion provided around the recess on the bottom surface. The electrode body portion is made up of a plurality of laminated metal layers and has a base layer located at an innermost side of the plurality of metal layers in a lamination direction of the multilayer body. The base layer is formed on the bottom surface at a position spaced apart from a short-side ridge portion between the bottom surface and one of the short-side side surfaces. Here, the "innermost side" means a position closest to the magnetic substrate among the plurality of laminated metal layers.

With this configuration, since the base layer is formed on the bottom surface at a position spaced apart from the

2

short-side ridge portion between the bottom surface and one of the side surfaces, an elongation of the base layer along the short-side ridge portion by barrel polishing and the like is suppressed. An elongation of the base layer along the short-side ridge portion is suppressed, so it is possible to suppress stress concentration on the portion. Therefore, it is possible to suppress occurrence of a fracture of the substrate and a crack of the outer electrode around the portion.

Other features, elements, characteristics and advantages of the present disclosure will become more apparent from the following detailed description of preferred embodiments of the present disclosure with reference to the attached drawings.

15 BRIEF DESCRIPTION OF THE DRAWINGS

FIG. 1 is a perspective view of a coil component according to an embodiment;

20 FIG. 2 is an exploded perspective view of the coil component according to the embodiment;

FIG. 3 is a cross-sectional view for illustrating the structure of each outer electrode of the coil component according to the embodiment;

25 FIG. 4 is a plan view for illustrating first metal layers of the outer electrodes of the coil component according to the embodiment;

FIG. 5 is a plan view for illustrating second metal layers of the outer electrodes of the coil component according to the embodiment;

30 FIG. 6 is a plan view for illustrating third metal layers of the outer electrodes of the coil component according to the embodiment;

FIG. 7 is a plan view for illustrating fourth metal layers and fifth metal layers of the outer electrodes of the coil component according to the embodiment;

35 FIG. 8 is a view for illustrating the multilayer structure of each outer electrode of the coil component according to the embodiment;

40 FIG. 9 is a view for illustrating a manufacturing method for the coil component according to the embodiment;

FIG. 10 is a view for illustrating the manufacturing method for the coil component according to the embodiment;

45 FIG. 11 is a view for illustrating the manufacturing method for the coil component according to the embodiment;

FIG. 12 is a view for illustrating the manufacturing method for the coil component according to the embodiment;

50 FIG. 13 is a view for illustrating the manufacturing method for the coil component according to the embodiment;

55 FIG. 14 is a view for illustrating the manufacturing method for the coil component according to the embodiment;

FIG. 15 is a view for illustrating the manufacturing method for the coil component according to the embodiment;

60 FIG. 16 is a view for illustrating the manufacturing method for the coil component according to the embodiment;

65 FIG. 17 is a view for illustrating the manufacturing method for the coil component according to the embodiment;

FIG. 18 is a view for illustrating the manufacturing method for the coil component according to the embodiment.

DETAILED DESCRIPTION

Hereinafter, an embodiment will be described with reference to the accompanying drawings.

The accompanying drawings may illustrate components in a magnified view for the sake of easy understanding. The scale ratio of components may be different from actual ones or those in other drawings.

As shown in FIG. 1, a coil component 10 has a substantially rectangular parallelepiped shape. The coil component 10 includes a first substrate 11, a second substrate 12, a multilayer body 13, and outer electrodes 14a, 14b, 14c, 14d. The first substrate 11 and the second substrate 12 are laminated so as to sandwich the multilayer body 13.

In FIG. 1, a lamination direction D of the first substrate 11, the multilayer body 13, and the second substrate 12 in the coil component 10 is defined as Z-axis direction, and a direction in which the long sides of the coil component 10 extend is defined as X-axis direction and a direction in which the short sides of the coil component 10 extend is defined as Y-axis direction when viewed in the Z-axis direction. In the Z-axis direction, a side where the outer electrodes 14a to 14d of the coil component 10 are present is defined as lower side, and a side across from the lower side is defined as upper side.

As shown in FIG. 1 and FIG. 2, the first substrate 11 has a substantially sheet shape. The first substrate 11 has a substantially rectangular bottom surface 11a and a top surface 11b located across from the bottom surface 11a. The top surface 11b faces the multilayer body 13 in the Z-axis direction, and the bottom surface 11a faces away from the multilayer body 13 in the Z-axis direction.

As shown in FIG. 1, the first substrate 11 has two side surfaces 11c, 11d connecting the bottom surface 11a and the top surface 11b and facing in the X-axis direction, and two side surfaces 11e, 11f connecting the bottom surface 11a and the top surface 11b and facing in the Y-axis direction. The two side surfaces 11c, 11d facing in the X-axis direction face away from each other. The two side surfaces 11e, 11f facing in the Y-axis direction face away from each other. The first substrate 11 has short-side ridge portions 71 and long-side ridge portions 72. One of the short-side ridge portions 71 is between the bottom surface 11a and the side surface 11c, and the other one of the short-side ridge portions 71 is between the bottom surface 11a and the side surface 11d. One of the long-side ridge portions 72 is between the bottom surface 11a and the side surface 11e, and the other one of the long-side ridge portions 72 is between the bottom surface 11a and the side surface 11f.

Here, in this specification, the "substantially rectangular shape" includes such a shape that at least one of the four corner portions of the substantially rectangular shape is cut out. In other words, in the bottom surface 11a serving as a bottom surface, such a shape of the bottom surface 11a that four corner portions each formed by extending the short-side ridge portion 71 and the long-side ridge portion 72 are cut out in a substantially circular arc shape toward the center of the bottom surface 11a is also included in the substantially rectangular shape. The shape of the first substrate 11 may be regarded as a substantially rectangular parallelepiped shape having the substantially rectangular bottom surface 11a.

The first substrate 11 has recesses 15a, 15b, 15c, 15d recessed toward the center of the first substrate 11 at the four

corner portions when viewed in a direction perpendicular to the bottom surface 11a. In other words, each of the recesses 15a, 15b, 15c, 15d provides a substantially circular arc connection ridge portion 73 at the bottom surface 11a and is formed such that the diameter of the circular arc gradually reduces toward the top surface 11b.

The first substrate 11 is a magnetic substrate. An example of the magnetic substrate is a ferrite sintered body. The first substrate 11 may be a resin molded body containing magnetic powder. The magnetic powder is, for example, ferrite or a metal magnetic material, such as iron (Fe), silicon (Si), and chromium (Cr), and the resin material is, for example, a resin material, such as epoxy. When the first substrate 11 is a resin containing magnetic powder, it is desirable that magnetic powder is adequately dispersed in a resin when two or more types of magnetic powder having different particle size distributions are mixed.

As shown in FIG. 2, the multilayer body 13 includes a plurality of electrically insulating layers 21a to 21c, coils 22a, 22b, and an adhesion layer 23, laminated on the top surface 11b of the first substrate 11. In the multilayer body 13, the direction in which the electrically insulating layers 21a to 21c, the coils 22a, 22b, and the adhesion layer 23 are laminated coincides with the lamination direction D and the Z-axis direction. The multilayer body 13 may be configured such that, for example, there is no interlayer interface or no other interface between the electrically insulating layers 21a to 21c.

As shown in FIG. 2, the electrically insulating layers 21a to 21c are laminated so as to be arranged in order of the electrically insulating layer 21a, the electrically insulating layer 21b, and the electrically insulating layer 21c from the first substrate 11 side in the Z-axis direction. The electrically insulating layers 21a to 21c have substantially the same size as the top surface 11b of the first substrate 11. The electrically insulating layer 21a has cutout portions C1a to C1d at four corners. The electrically insulating layer 21b has cutout portions C2a to C2d at four corners. The electrically insulating layer 21c has a via hole H1 extending through in the Z-axis direction. Among the four corners of the electrically insulating layer 21c, cutout portions C3b, C3d are provided at both end portions at one side in the Y-axis direction. The electrically insulating layer 21c has via holes H2, H3 extending through in the Z-axis direction.

The cutout portion C1a and the cutout portion C2a are provided at positions that overlap the outer electrode 14a in the Z-axis direction. The cutout portion C1b, the cutout portion C2b, and the cutout portion C3b are provided at positions that overlap the outer electrode 14b in the Z-axis direction. The cutout portion C1c and the cutout portion C2c are provided at positions that overlap the outer electrode 14c in the Z-axis direction. The cutout portion C1d, the cutout portion C2d, and the cutout portion C3d are provided at positions that overlap the outer electrode 14d in the Z-axis direction.

The electrically insulating layers 21a to 21c may be made by using various resin materials, such as polyimide resin, epoxy resin, phenolic resin, and benzocyclobutene resin.

The coil 22a includes a coil conductor 31 and extended portions 32, 33, 34, 35, 36, 37.

The coil conductor 31 is provided between the electrically insulating layer 21a and the electrically insulating layer 21b and has a substantially flat spiral shape that approaches the center while winding in a clockwise direction when viewed in plan from the upper side in the Z-axis direction. The

center of the coil conductor 31 coincides with the center of the coil component 10 when viewed in plan in the Z-axis direction.

The extended portion 32 is connected to an outer end portion of the coil conductor 31. The extended portion 32 is extended to the cutout portion C1c of the electrically insulating layer 21a. The extended portion 32 extends through the electrically insulating layer 21a in the Z-axis direction via the cutout portion C1c. The extended portion 32 is extended to the cutout portion C2c of the electrically insulating layer 21b and is connected to the extended portion 33 provided at the cutout portion C2c.

The thus configured extended portion 32 is connected to the end portion of the coil conductor 31 and is extended to the cutout portion C1c of the electrically insulating layer 21a that makes up the multilayer body 13. Thus, the extended portion 32 is exposed to the recess 15c when viewed in plan from the lower side toward the upper side in the Z-axis direction.

The extended portion 34 extends through the electrically insulating layer 21b in the Z-axis direction via the via hole H1, thus being connected to an inner end portion of the coil conductor 31.

The extended portion 35 is connected to the extended portion 34 such that a first end side extends through the electrically insulating layer 21c in the Z-axis direction via the via hole H3. A second end side of the extended portion 35 is extended to the cutout portion C3d of the electrically insulating layer 21c. The extended portion 35 extends through the electrically insulating layer 21c in the Z-axis direction via the cutout portion C3d.

The extended portion 36 is provided at the cutout portion C2d of the electrically insulating layer 21b. Thus, the extended portion 36 is connected to the second end side of the extended portion 35. The extended portion 36 extends through the electrically insulating layer 21b in the Z-axis direction via the cutout portion C2d.

The extended portion 37 is provided at the cutout portion C1d of the electrically insulating layer 21a. Thus, the extended portion 37 is connected to the extended portion 36. The extended portion 37 extends through the electrically insulating layer 21a in the Z-axis direction via the cutout portion C1d.

The thus configured extended portions 34 to 37 are connected to the end portion of the coil conductor 31 and are extended to the cutout portion C1d of the electrically insulating layer 21a that makes up the multilayer body 13. Thus, the extended portion 37 is exposed to the recess 15d when viewed in plan from the lower side toward the upper side in the Z-axis direction.

The coil 22b includes a coil conductor 41 and extended portions 42, 43, 44, 45, 46.

The coil conductor 41 is provided between the electrically insulating layer 21b and the electrically insulating layer 21c and has a substantially flat spiral shape that approaches the center while winding in a clockwise direction when viewed in plan from the upper side in the Z-axis direction. In other words, the coil conductor 41 winds in the same direction as the coil conductor 31. The center of the coil conductor 41 coincides with the center of the coil component 10 when viewed in plan in the Z-axis direction. Thus, the coil conductor 41 overlaps the coil conductor 31 when viewed in plan in the Z-axis direction.

The extended portion 42 is connected to an outer end portion of the coil conductor 41. The extended portion 42 is extended to the cutout portion C2a of the electrically insu-

lating layer 21b. The extended portion 42 extends through the electrically insulating layer 21b in the Z-axis direction via the cutout portion C2a.

The extended portion 43 is provided at the cutout portion C1a of the electrically insulating layer 21a. Thus, the extended portion 43 is connected to the extended portion 42. The extended portion 43 extends through the electrically insulating layer 21a in the Z-axis direction via the cutout portion C1a.

10 The thus configured extended portions 42, 43 are connected to the end portion of the coil conductor 41 and are extended to the cutout portion C1a. Thus, the extended portion 43 is exposed to the recess 15a when viewed in plan from the lower side toward the upper side in the Z-axis direction.

A first end side of the extended portion 44 extends through the electrically insulating layer 21c in the Z-axis direction via the via hole H2, thus being connected to an inner end portion of the coil conductor 41. A second end side of the 20 extended portion 44 is extended to the cutout portion C3b of the electrically insulating layer 21c. The extended portion 44 extends through the electrically insulating layer 21c in the Z-axis direction via the cutout portion C3b.

The extended portion 45 is provided at the cutout portion C2b of the electrically insulating layer 21b. Thus, the extended portion 45 is connected to the extended portion 44. The extended portion 45 extends through the electrically insulating layer 21b in the Z-axis direction via the cutout portion C2b.

30 The extended portion 46 is provided at the cutout portion C1b of the electrically insulating layer 21a. Thus, the extended portion 46 is connected to the extended portion 45. The extended portion 46 extends through the electrically insulating layer 21a in the Z-axis direction via the cutout portion C1b.

The thus configured extended portions 44 to 46 are connected to the end portion of the coil conductor 41 by the extended portion 44 and are extended to the cutout portion C1b by the extended portion 46 connected to the extended portion 44 via the extended portion 45. Thus, the extended portion 46 is exposed to the recess 15b when viewed in plan from the lower side toward the upper side in the Z-axis direction.

The second substrate 12 has a substantially sheet shape. The second substrate 12 has a bottom surface 12a and a top surface 12b facing away from the bottom surface 12a. The bottom surface 12a faces the multilayer body 13 in the Z-axis direction, and the top surface 12b faces away from the multilayer body 13 in the Z-axis direction. The second substrate 12 is, for example, a magnetic substrate as an example of a magnetic layer. The second substrate 12 is made of, for example, any one of the materials exemplified for the first substrate 11. The second substrate 12 is bonded to the top surface of the multilayer body 13 with the adhesion layer 23 interposed therebetween. For example, thermosetting polyimide resin may be used as the adhesion layer 23. The second substrate 12 may be made up of a magnetic layer other than the magnetic substrate.

Each of the outer electrodes 14a, 14b, 14c, 14d has an 60 electrode body portion 51 and a connection portion 52 connecting the electrode body portion 51 and the coil 22a or the coil 22b.

The electrode body portion 51 of each of the outer electrodes 14a, 14b, 14c, 14d is formed around an associated 65 one of the recesses 15a to 15d on the bottom surface 11a (bottom surface) of the first substrate 11. More specifically, the electrode body portion 51 of the outer electrode 14a is

formed around the recess **15a**. The electrode body portion **51** of the outer electrode **14b** is formed around the recess **15b**. The electrode body portion **51** of the outer electrode **14c** is formed around the recess **15c**. The electrode body portion **51** of the outer electrode **14d** is formed around the recess **15d**.

The connection portion **52** of each of the outer electrodes **14a**, **14b**, **14c**, **14d** is formed at an associated one of the recesses **15a** to **15d** of the first substrate **11**. More specifically, the connection portion **52** of the outer electrode **14a** is formed at the recess **15a**. The connection portion **52** of the outer electrode **14b** is formed at the recess **15b**. The connection portion **52** of the outer electrode **14c** is formed at the recess **15c**. The connection portion **52** of the outer electrode **14d** is formed at the recess **15d**.

The outer electrodes **14a**, **14b**, **14c**, **14d** are respectively formed at the four corners of the bottom surface **11a** that is the bottom surface of the first substrate **11**. The outer electrodes **14a**, **14b**, **14c**, **14d** are connected by solder or the like to a land pattern of a mounting substrate for mounting the coil component **10**.

Each of the outer electrodes **14a**, **14b**, **14c**, **14d** is made so as to have a substantially rectangular shape when viewed from the lower side toward the upper side in the Z-axis direction. A short-side direction of each of the outer electrodes **14a**, **14b**, **14c**, **14d** coincides with a short-side direction of the bottom surface **11a** of the first substrate **11**. A long-side direction of each of the outer electrodes **14a**, **14b**, **14c**, **14d** coincides with a long-side direction of the bottom surface **11a** of the first substrate **11**. Here, the case in which the sides of the outer electrodes **14a**, **14b**, **14c**, **14d** are straight and the case in which the sides are slightly wavy are included. The long-side direction of each of the outer electrodes **14a**, **14b**, **14c**, **14d** does not need to coincide with the long-side direction of the bottom surface **11a**. The short-side direction of each of the outer electrodes **14a**, **14b**, **14c**, **14d** does not need to coincide with the short-side direction of the bottom surface **11a**.

Each of the outer electrodes **14a**, **14b**, **14c**, **14d** is made up of a plurality of laminated metal layers.

As shown in FIG. 3, the plurality of metal layers includes a first metal layer **61**, a second metal layer **62**, a third metal layer **63**, a fourth metal layer **64**, and a fifth metal layer **65**. Here, the connection portions **52** of the outer electrodes **14a**, **14b**, **14c**, **14d** have the same multilayer structure as the electrode body portions **51** of the outer electrodes **14a**, **14b**, **14c**, **14d**. In other words, when the electrode body portion **51** includes the first metal layer **61**, the second metal layer **62**, the third metal layer **63**, the fourth metal layer **64**, and the fifth metal layer **65**, the connection portion **52** also similarly includes the first metal layer **61**, the second metal layer **62**, the third metal layer **63**, the fourth metal layer **64**, and the fifth metal layer **65**.

The first metal layer **61** is provided on the bottom surface **11a** of the first substrate **11**. The first metal layer **61** is located at an innermost side of the metal layers **61** to **65** in the Z-axis direction. In other words, the first metal layer **61** corresponds to a base layer. The first metal layer **61** is a metal thin film containing titanium (Ti) as a main ingredient. The first metal layer **61** is formed by, for example, sputtering. The first metal layer **61** has, for example, a thickness of greater than or equal to about 100 nm and less than or equal to about 200 nm (i.e., from about 100 nm to about 200 nm).

As shown in FIG. 4, the first metal layer **61** of the electrode body portion **51** is formed at a position spaced apart from the short-side ridge portion **71** of the first substrate **11**. At this time, the first metal layer **61** of the

electrode body portion **51** is formed at a position that borders the long-side ridge portion **72** of the first substrate **11**.

The second metal layer **62** is provided on the first metal layer **61**. The second metal layer **62** is made of a material having a lower electrical resistance than that of the first metal layer **61**. More specifically, the second metal layer **62** is a metal thin film containing copper (Cu) as a main ingredient. The second metal layer **62** is formed by, for example, sputtering. The second metal layer **62** has, for example, a thickness of greater than or equal to about 100 nm and less than or equal to about 200 nm (i.e., from about 100 nm to about 200 nm).

As shown in FIG. 5, the second metal layer **62** of the electrode body portion **51** is formed at a position spaced apart from the short-side ridge portion **71** of the first substrate **11**. At this time, the second metal layer **62** of the electrode body portion **51** is formed at a position that borders the long-side ridge portion **72** of the first substrate **11**. The second metal layer **62** of the electrode body portion **51** corresponds to a low resistance layer.

The third metal layer **63** is provided on the second metal layer **62**. The third metal layer **63** is made of a material having a lower electrical resistance than that of the first metal layer **61**. More specifically, the third metal layer **63** is a metal film containing copper (Cu) as a main ingredient. The third metal layer **63** is formed by, for example, electrolytic plating. The third metal layer **63** has, for example, a thickness of about 10 μm .

As shown in FIG. 6, the third metal layer **63** of the electrode body portion **51** is formed at a position spaced apart from the short-side ridge portion **71** of the first substrate **11**. At this time, the third metal layer **63** of the electrode body portion **51** is formed at a position that borders the long-side ridge portion **72** of the first substrate **11**. The third metal layer **63** of the electrode body portion **51** corresponds to a low resistance layer.

As shown in FIG. 6, the third metal layer **63** of the connection portion **52** is formed so as to entirely cover the connection portion **52**. At this time, the third metal layer **63** is formed up to a position that overlaps a recess ridge portion **74** of an associated one of the recesses **15a** to **15d** continuous in a direction from the short-side ridge portion **71** toward the top surface **11b**. At this time, the third metal layer **63** is formed up to a position that overlaps a ridge portion **75** of an associated one of the recesses **15a** to **15d** continuous in a direction from the long-side ridge portion **72** toward the top surface **11b**.

The fourth metal layer **64** shown in FIG. 7 is provided on the third metal layer **63**. The fourth metal layer **64** is a metal film containing nickel (Ni) as a main ingredient. The fourth metal layer **64** is formed by, for example, electrolytic plating. The fourth metal layer **64** has, for example, a thickness of about 3 μm . The fourth metal layer **64** has a length of about 72 μm in the short-side direction, and has a tolerance of about 10 μm . An elongation of the fourth metal layer **64** along the short-side ridge portion **71** of the bottom surface **11a** is less than or equal to about 11 μm . More preferably, the elongation is less than or equal to about 5 μm . The fourth metal layer **64** corresponds to a coating layer provided on the third metal layer **63** that makes up the low resistance layer. Here, the coating layer protects the third metal layer **63** that makes up the low resistance layer by covering the third metal layer **63**. In other words, with the fourth metal layer **64** made of nickel, it is possible to suppress occurrence of so-called copper erosion in the third metal layer **63**.

The fifth metal layer **65** shown in FIG. 7 is provided on the fourth metal layer **64**. The fifth metal layer **65** is a metal film containing tin (Sn) as a main ingredient. The fifth metal layer **65** is formed by, for example, electrolytic plating. The fifth metal layer **65** has, for example, a thickness of about 3 μm . The fifth metal layer **65** has a length of about 75 μm in the short-side direction, and has a tolerance of about 10 μm . An elongation of the fifth metal layer **65** along the short-side ridge portion **71** of the bottom surface **11a** is preferably less than or equal to about 13 μm .

In the thus configured coil component **10**, when the first substrate **11**, the multilayer body **13**, and the second substrate **12** are laminated as a laminate, the laminate has a length of about 0.23 mm in the lamination direction D (Z-axial direction), a length of about 0.3 mm in the Y-axis direction that is the short-side direction among directions perpendicular to the lamination direction D, and a length of about 0.45 mm in the X-axis direction that is the long-side direction among the directions perpendicular to the lamination direction D. A tolerance of the length in each of the three axial directions is about ± 0.02 mm.

As shown in FIG. 8, where, in the electrode body portion **51** adjacent to the recess **15c** in a direction along the short side of the bottom surface **11a**, an end portion at a position spaced apart from the recess **15c** in the direction along the short side is defined as a distant end portion **51a**, a distance **L1** in the direction along the short side between the recess **15c** and the distant end portion **51a** is preferably less than or equal to about 25 μm . More specifically, a distance **L1** from the recess **15c** to a distant end portion **63a** of the third metal layer **63** in the electrode body portion **51** is preferably less than or equal to about 25 μm . Although the recess **15c** and the electrode body portion **51** around the recess **15c** are specifically described, the other recesses **15a**, **15b**, **15d** and the electrode body portions **51** around the other recesses **15a**, **15b**, **15d** are also preferably set to the distance **L1** as described above.

A distance **L2** from the short-side ridge portion **71** to the electrode body portion **51** in the long-side direction of the bottom surface **11a**, shown in FIG. 8, is preferably greater than or equal to about 3.3 μm and less than or equal to about 16.7 μm (i.e., from about 3.3 μm to about 16.7 μm). Although the electrode body portion **51** and the short-side ridge portion **71** around the recess **15c** are specifically described in FIG. 8, the electrode body portions **51** and the short-side ridge portions **71** around the other recesses **15a**, **15b**, **15d** are also preferably set to the distance **L2** as described above. At this time, the distances **L2** respectively associated with the recesses **15a**, **15b**, **15c**, **15d** may be equal to one another or may be different from one another.

As shown in FIG. 8, the recess **15c** has a radius **R1** of about 62 μm after the fourth metal layer **64** is formed, and has a tolerance of about ± 15 μm . The recess **15c** has a radius **R1** of about 55 μm after the fifth metal layer **65** is formed, and has a tolerance of about ± 15 μm . FIG. 8 is schematically shown, and the origin position of the radius **R1** can be different from an actual one. Not limited to the radius **R1** of the recess **15c**, the other recesses **15a**, **15b**, **15d** are also preferably set to the radius **R1**.

The operation of the thus configured coil component **10** will be described below. The outer electrodes **14a**, **14c** are used as input terminals. The outer electrodes **14b**, **14d** are used as output terminals.

Differential transmission signals composed of a first signal and a second signal that are different in phase by 180 degrees are respectively input to the outer electrodes **14a**, **14c**. Because the first signal and the second signal are in a

differential mode, the first signal and the second signal generate mutually opposite magnetic fluxes in the coils **22a**, **22b** when passing through the coils **22a**, **22b**. The magnetic flux generated in the coil **22a** and the magnetic flux generated in the coil **22b** cancel out each other. Therefore, in each of the coils **22a**, **22b**, almost no variation in magnetic flux occurs due to flow of the first signal or the second signal. In other words, the coil **22a** or the coil **22b** does not generate counter-electromotive force that impedes flow of the first signal or the second signal. Thus, the coil component **10** has an extremely small impedance for the first signal and the second signal.

On the other hand, when the first signal and the second signal each contain common mode noise, the common mode noises respectively generate magnetic fluxes having the same direction in the coils **22a**, **22b** when passing through the coils **22a**, **22b**. Therefore, in each of the coils **22a**, **22b**, magnetic flux increases due to flow of the common mode noise. Thus, each of the coils **22a**, **22b** generates counter-electromotive force that impedes flow of the common mode noise. Thus, the coil component **10** has a large impedance for the first signal and the second signal.

Next, a manufacturing method for the coil component **10** will be described with reference to FIG. 9 to FIG. 18.

As shown in FIG. 9, positions corresponding to the recesses **15a**, **15b**, **15c**, **15d** of a photoresist PR1 on a bottom surface **M11a** of a mother substrate M11 are exposed to light while being aligned with the coil conductors **31**, **41** in a mother multilayer body M13. At this time, by placing a mask **Mk** at portions other than the recesses **15a** to **15d**, the positions corresponding to the recesses **15a**, **15b**, **15c**, **15d** of the photoresist PR1 are exposed to light as described above. The mother multilayer body M13 will be the multilayer body **13**, and is disposed between the mother substrate M11 that will be the first substrate **11** and a mother substrate M12 that will be the second substrate **12**. Hereinafter, a body made up of the mother substrate M11, the mother substrate M12, and the mother multilayer body M13 will be described as a mother body M. The mother multilayer body M13 includes conductor portions M13a that will be not only the coil conductors **31**, **41** but also the extended portions **32** to **37**, **42** to **46**.

Subsequently, as shown in FIG. 10, the photoresist PR1 is developed. Thus, the photoresist PR1 has openings PR1x corresponding to the recesses **15a**, **15b**, **15c**, **15d** and exposed to light.

After that, as shown in FIG. 11, through-holes H15 are formed at positions to form the recesses **15a**, **15b**, **15c**, **15d** in the mother substrate M11 by, for example, sand blast via the openings PR1x of the photoresist PR1. At this time, cutout portions N may be formed in the conductor portions M13a at positions corresponding to the through-holes H15 in the mother multilayer body M13. The through-holes H15 may be formed by laser beam machining other than sand blast or may be formed by a combination of sand blast and laser beam machining.

Then, as shown in FIG. 12, the photoresist PR1 is removed by using, for example, organic solvent.

Subsequently, as shown in FIG. 13, the first metal layer **61** and the second metal layer **62** are deposited by sputtering on all the bottom surface **M11a** of the mother body M (mother substrate M11).

After that, as shown in FIG. 14, a photoresist PR2 is formed on a flat portion around the through-holes H15 of the bottom surface **M11a**. In other words, the photoresist PR2 has openings PR2x at positions corresponding to the through-holes H15.

11

Then, as shown in FIG. 15, the third metal layers 63 are formed by electrolytic plating by using the first metal layer 61 and the second metal layer 62 as feeding films.

Subsequently, as shown in FIG. 16, the photoresist PR2 is removed by using organic solvent as in the case of the photoresist PR1. Then, the first metal layer 61 and the second metal layer 62, exposed from the third metal layers 63, are removed by, for example, wet etching or the like.

After that, as shown in FIG. 17, the mother substrate M12 is formed into a thin sheet shape by, for example, grinding or polishing.

Then, as shown in FIG. 18, the mother body M is cut along cut lines CL into a size of each coil component 10. Thus, the conductor portions M13a of the mother multilayer body M13 become the extended portions 32 to 37, 42 to 46. After cutting, chamfering is performed by barrel polishing or the like. At this time, since each third metal layer 63 of this example is formed at a position spaced apart from the short-side ridge portion 71, an elongation of the third metal layer 63 along the short-side ridge portion 71 is suppressed.

Subsequently, the outer electrodes 14a, 14b, 14c, 14d are formed by forming the fourth metal layers 64 and the fifth metal layers 65 in this order by using electrolytic plating. As a result, the coil component 10 is finished. When the fourth metal layer 64 and the fifth metal layer 65 are formed, an elongation of each third metal layer 63 along the short-side ridge portion 71 is suppressed as described above, so an elongation of the fourth metal layer 64 and an elongation of the fifth metal layer 65 along the short-side ridge portion 71 are also similarly suppressed.

According to the above-described present embodiment, the following advantageous effects are obtained.

(1) Since the first metal layer 61 serving as a base layer is formed at a position spaced apart from the short-side ridge portion 71 between the bottom surface 11a and the side surface 11c or the short-side ridge portion 71 between the bottom surface 11a and the side surface 11d on the bottom surface 11a, an elongation of the first metal layer 61 along the short-side ridge portion 71 by barrel polishing or the like is suppressed. Since an elongation of the first metal layer 61 along the short-side ridge portion 71 is suppressed, stress concentration on the portion is reduced. Therefore, it is possible to suppress occurrence of a fracture of the first substrate 11 and cracks of the outer electrodes 14a, 14b, 14c, 14d around the portions.

(2) Since the second metal layer 62 and the third metal layer 63 are formed at positions spaced apart from the short-side ridge portion 71 on the bottom surface 11a, an elongation of the second metal layer 62 and an elongation of the third metal layer 63 along the short-side ridge portion 71 due to barrel polishing or the like are suppressed. Since an elongation of the second metal layer 62 and an elongation of the third metal layer 63 along the short-side ridge portion 71 are suppressed, stress concentration on the portions is reduced. Therefore, it is possible to suppress occurrence of a fracture of the first substrate 11 and cracks of the outer electrodes 14a, 14b, 14c, 14d around the portions.

(3) For the outer electrodes 14a, 14b, 14c, 14d, even in the configuration that further includes the connection portions 52 provided in the recesses 15a, 15b, 15c, 15d and electrically connecting the coils 22a, 22b to the electrode body portions 51, since an elongation of the third metal layer 63 along the short-side ridge portion 71 is suppressed, stress concentration on the portion is reduced. Therefore, it is possible to suppress occurrence of a fracture of the first substrate 11 and cracks of the outer electrodes 14a, 14b, 14c, 14d around the portions.

12

(4) The third metal layer 63 of the connection portion 52 is formed at least at a position that overlaps the recess ridge portion 74 of an associated one of the recesses 15a to 15d continuous from the short-side ridge portion 71 toward the top surface 11b. In other words, in each of the recesses 15a to 15d, the third metal layer 63 and the connection portion 52 including the third metal layer 63 can be formed in a wide range. Therefore, when the coil component 10 is connected to a mounting substrate by solder, it is possible to contribute to improvement in connection reliability between solder and the connection portions 52 of the recesses 15a to 15d.

(5) Since the connection portion 52 has the same multi-layer structure as the electrode body portion 51, the connection portion 52 can be formed in the same manufacturing process as the electrode body portion 51.

(6) The plurality of metal layers 61 to 65 include the fourth metal layer 64 as the coating layer on the third metal layer 63 that makes up the low resistance layer. Because an elongation of the third metal layer 63 along the short-side ridge portion 71 is suppressed, an elongation of the fourth metal layer 64 along the short-side ridge portion 71 is also similarly suppressed.

(7) The third metal layer 63 that makes up the low resistance layer is a metal layer containing copper, and the fourth metal layer 64 that is the coating layer has a metal layer containing nickel. By suppressing an elongation of the fourth metal layer 64 containing nickel along the short-side ridge portion 71, erosion of the first substrate 11 by the fourth metal layer 64 is suppressed, so it is possible to contribute to improvement in close contact between each of the outer electrodes 14a, 14b, 14c, 14d and the first substrate 11.

(8) When the first substrate 11, the multilayer body 13, and the second substrate 12 are laminated as a laminate, the laminate has a length of less than or equal to about 0.23 mm in the lamination direction D, a length of less than or equal to about 0.3 mm in a direction along the short side among directions perpendicular to the lamination direction D, and a length of less than or equal to about 0.45 mm in a direction along the long side among the directions perpendicular to the lamination direction D. In this way, it is possible to suppress an elongation along the short-side ridge portion 71 as described above in the small-sized coil component.

(9) Since the distance L1 from each of the recesses 15a to 15d to the distant end portion 51a of the electrode body portion 51 adjacent to the same one of the recesses 15a to 15d in the direction along the short side is less than or equal to about 25 μ m, it is possible to suppress proximity between the electrode body portions 51, so it is possible to suppress occurrence of leak current. Thus, an L value improves, so noise cancellation capability improves.

(10) When the distance L2 from the short-side ridge portion 71 to the electrode body portion 51 is greater than or equal to about 3.3 μ m and less than or equal to about 16.7 μ m (i.e., from about 3.3 μ m to about 16.7 μ m), an elongation of the electrode body portion 51 along the short-side ridge portion 71 is suitably suppressed.

(Other Embodiments)

The above-described embodiment may be modified as follows. The above-described embodiment and the following modifications may be implemented in combination without any technical contradiction.

In the above-described embodiment, each of the outer electrodes 14a, 14b, 14c, 14d is made up of five metal layers 61, 62, 63, 64, 65; however, the configuration is not limited

13

thereto. Alternatively, each of the outer electrodes **14a**, **14b**, **14c**, **14d** may be made up of four or less or six or more layers.

In the above-described embodiment, the recesses **15a**, **15b**, **15c**, **15d** are respectively provided at four corner portions; however, the configuration is not limited thereto. For example, a recess may be added to the center of the bottom surface **11a** of the first substrate **11**. Alternatively, another recess may be added between the recess **15a** and the recess **15c** or between the recess **15b** and the recess **15d**.

In the above-described embodiment, the third metal layer **63** is formed at a position spaced apart from the short-side ridge portion **71**. In addition to this, the third metal layer **63** may be formed at a position spaced apart from the long-side ridge portion **72**.

In the above-described embodiment, the coil component **10** includes four outer electrodes **14a**, **14b**, **14c**, **14d**; however, the configuration is not limited thereto. The coil component **10** may include six outer electrodes. In this case, an outer electrode is provided between the outer electrode **14a** and the outer electrode **14c** arranged in the long-side direction (X-axis direction) of the coil component **10**, and an outer electrode is provided between the outer electrode **14b** and the outer electrode **14d** arranged in the long-side direction (X-axis direction) of the coil component **10**.

In the above-described embodiment, the coil component **10** including a flat spiral coil conductor is employed; however, the configuration is not limited thereto. For example, a coil component may include a three-dimensional spiral (helical) coil conductor in which a spiral advances in the lamination direction D.

In the above-described embodiment, the first metal layer **61** serving as the base layer and the second and third metal layers **62**, **63** serving as the low resistance layers are provided at positions spaced apart from the short-side ridge portion **71**; however, the configuration is not limited thereto. For example, only the base layer may be provided at a position spaced apart from the short-side ridge portion **71**.

In the above-described embodiment, the low resistance layer is made up of two layers, that is, the second metal layer **62** and the third metal layer **63**; however, the configuration is not limited thereto. The low resistance layer may be made up of one or three or more layers.

In the above-described embodiment, the connection portion **52** has the same multilayer structure as the electrode body portion **51**; however, the configuration is not limited thereto. The connection portion and the electrode body portion may have different multilayer structures. For example, the number of laminated layers may be varied between the connection portion and the electrode body portion.

While preferred embodiments of the disclosure have been described above, it is to be understood that variations and modifications will be apparent to those skilled in the art without departing from the scope and spirit of the disclosure. The scope of the disclosure, therefore, is to be determined solely by the following claims.

What is claimed is:

1. A coil component comprising:

a magnetic substrate having a rectangular bottom surface having a pair of long sides and a pair of short sides, a top surface located across from the bottom surface, and a pair of long-side side surfaces and a pair of short-side side surfaces each connecting the bottom surface and the top surface, and the magnetic substrate having a recess at a corner portion of the bottom surface;

14

a multilayer body having an electrically insulating layer on the top surface and a coil in the electrically insulating layer; and

an outer electrode provided on the bottom surface, the outer electrode having an electrode body portion provided around the recess on the bottom surface, the electrode body portion being made up of a plurality of laminated metal layers and having a base layer located at an innermost side of the plurality of metal layers in a lamination direction of the multilayer body, and the base layer being on the bottom surface at a position spaced apart from a short-side ridge portion between the bottom surface and one of the short-side side surfaces,

wherein

in the electrode body portion adjacent to the recess in a direction along the short side, an end portion at a position spaced apart from the recess in the direction along the short side is defined as a distant end portion, a distance in the direction along the short side between the recess and the distant end portion is less than or equal to 25 μm .

2. The coil component according to claim 1, wherein the plurality of metal layers includes a low resistance layer on the base layer, the low resistance layer being lower in electrical resistance than the base layer, and the low resistance layer is at a position spaced apart from the short-side ridge portion on the bottom surface.

3. The coil component according to claim 1, wherein the outer electrode further includes a connection portion at the recess and electrically connecting the coil and the electrode body portion.

4. The coil component according to claim 3, wherein the connection portion is integrated with the electrode body portion and configured from the electrode body portion onto a recess ridge portion between the recess and the one of the short-side side surfaces.

5. The coil component according to claim 3, wherein the connection portion has the same multilayer structure as the electrode body portion.

6. The coil component according to claim 2, wherein the plurality of metal layers includes a coating layer on the low resistance layer.

7. The coil component according to claim 6, wherein the low resistance layer is a metal layer containing copper, and

the coating layer has a metal layer containing nickel.

8. The coil component according to claim 1, further comprising:

a magnetic layer on the multilayer body, wherein when the magnetic substrate, the multilayer body, and the magnetic layer are laminated as a laminate, the laminate has

a length of 0.23 mm or less in a lamination direction, a length of 0.3 mm or less in a direction along the short side in directions perpendicular to the lamination direction, and

a length of 0.45 mm or less in a direction along the long side in the directions perpendicular to the lamination direction.

9. The coil component according to claim 2, wherein the outer electrode further includes a connection portion at the recess and electrically connecting the coil and the electrode body portion.

10. The coil component according to claim 4, wherein the connection portion has the same multilayer structure as the electrode body portion.

15

11. The coil component according to claim 3, wherein the plurality of metal layers includes a low resistance layer and a coating layer on the low resistance layer.
12. The coil component according to claim 4, wherein the plurality of metal layers includes a low resistance layer and a coating layer on the low resistance layer.
13. The coil component according to claim 5, wherein the plurality of metal layers includes a low resistance layer and a coating layer on the low resistance layer.
14. The coil component according to claim 2, further comprising:
 a magnetic layer on the multilayer body, wherein when the magnetic substrate, the multilayer body, and the magnetic layer are laminated as a laminate, the laminate has
 a length of 0.23 mm or less in a lamination direction, a length of 0.3 mm or less in a direction along the short side in directions perpendicular to the lamination direction, and
 a length of 0.45 mm or less in a direction along the long side in the directions perpendicular to the lamination direction.
15. The coil component according to claim 3, further comprising:
 a magnetic layer on the multilayer body, wherein

5

15

16

when the magnetic substrate, the multilayer body, and the magnetic layer are laminated as a laminate, the laminate has

a length of 0.23 mm or less in a lamination direction, a length of 0.3 mm or less in a direction along the short side in directions perpendicular to the lamination direction, and

a length of 0.45 mm or less in a direction along the long side in the directions perpendicular to the lamination direction.

16. The coil component according to claim 4, further comprising:

a magnetic layer on the multilayer body, wherein when the magnetic substrate, the multilayer body, and the magnetic layer are laminated as a laminate, the laminate has

a length of 0.23 mm or less in a lamination direction, a length of 0.3 mm or less in a direction along the short side in directions perpendicular to the lamination direction, and

a length of 0.45 mm or less in a direction along the long side in the directions perpendicular to the lamination direction.
